CIGARETTE HOLDING DEVICE

Charles A. Ford, Elizabeth, N. J.

Application June 3, 1953, Serial No. 359,381

1 Claim. (Cl. 131—256)

This invention relates to improvements in cigarette holding devices comprising a resilient tongs structure by which a burning cigarette can be supported during the smoking thereof. The invention has for an object to provide a resilient tongs device adapted to be held in the smoker's hand and provided with gripping jaw portions, which are yieldably biased one toward the other, by and between which an ignited cigarette can be held during smoking thereof, thus avoiding necessity for holding the cigarette between the smoker's fingers, and consequently avoiding risk of resultant nicotine staining of the fingers.

The invention has for a further object to provide a cigarette holding tongs comprising a one-piece body formation produced from stiff springy wire doubled upon itself to provide a pair of leg members tensionally biased for relative outward movement, and terminating in opposed cigarette gripping jaws yieldably biased by said leg members for movement one toward the other to cigarette gripping positions; said jaws being formed to include means to so limit their cigarette gripping movement one toward the other that, although firm holding engagement of a cigarette is assured, nevertheless the gripping action is so restrained that undue squeezing constriction of the cigarette is prevented, and consequent impedance to draw of smoke through the cigarette is avoided; and the gripping jaws being also so formed as to limit opening movement of the same, whereby impairment of the spring action of the tongs' leg members, by which said jaws are supported and biased, is likewise avoided.

The above and other objects will be understood from a reading of the following detailed description of this invention in connection with the accompanying drawings, in which:

Fig. 1 is a side edge elevational view of one embodiment of this invention showing a cigarette applied thereto and held thereby; Fig. 2 is a face view of the same; and Fig. 3 is a face view similar to that of Fig. 2, but showing the gripping jaws in cigarette releasing position.

Fig. 4 is a side edge elevational view of a modified embodiment of this invention, showing a cigarette applied thereto and held thereby; Fig. 5 is a face view of the same; and Fig. 6 is a face view similar to that of Fig. 5, but showing the gripping jaws in cigarette releasing position.

Similar characters of reference are employed in the herein above described views, to indicate corresponding parts.

The cigarette holding tongs according to this invention, as shown in Figs. 1 to 3 inclusive, comprises a one-piece body formation produced from stiff springy wire doubled upon itself into a U-shape to provide a resilient closed lower end 10, from which extend laterally spaced apart leg members 11 and 12. Extending inwardly from the free end of the leg member 11,

2

as an integral part thereof, is an arm 13. In like manner, extending inwardly from the free end of the opposite leg member 12, as an integral part thereof, is an arm 14. The inner face of the arm 13 overlaps the inner face of the arm 14. The arm 13 terminates in a downwardly directed arcuate gripping jaw member 15, which is open toward the leg member 11, and from which extends, toward the latter, a tail piece 16. Similarly, the arm 14 terminates in a downwardly directed arcuate gripping jaw member 17, which is open toward the leg member 12, and from which a tail piece 18 extends toward said leg member 12. The tail piece 16 crosses the tail piece 18, the outer faces thereof being overlapped. Said tail pieces are outwardly bowed respectively in opposite directions relative to the plane of the leg members 11 and 12. The interiors of the jaw members 15 and 17 are opposed one to the other, and are yieldably urged one toward the other by the outwardly biasing tension exerted upon the leg members 11 and 12 by the resilient closed end 10 of the tongs device.

By reason of the lapped relation of the inner faces of the arms 13 and 14 and the bowed formation and lapped crossed relation of the outer faces of the tail pieces 16 and 18, relative movement of the jaw members 15 and 17 toward one another is limited by mutual engagement of intersecting portions of the lapped arms 13 and 14 and lapped tail pieces 16 and 18, and consequently said jaw members, although free to close upon a cigarette inserted therebetween with adequate grip thereupon for firm holding support thereof, cannot close sufficiently to exert undue constrictive squeezing action upon the cigarette likely to impede drawing of smoke therethrough by the smoker. On the other hand, the bowed formation of the tail pieces 16 and 18 disposes the junctures thereof with the respective jaw portions 15 and 17 in the plane of and opposed to inner sides of the respective leg members 11 and 12, whereby inward movement of the latter, in opposition to the biased tension thereof, is limited by engagement with said junctures of the aforesaid parts (see Fig. 3). By pressing the leg members 11 and 12 one toward the other, in directions of the arrows in Fig. 3, the jaw portions 15 and 17 are separated for reception or release of a cigarette, as the case may be.

In Figs. 4 to 6 inclusive there is shown a somewhat modified form of the cigarette holding tongs of this invention, the same also comprising a one-piece body formation produced from stiff springy wire doubled upon itself into a U-shape to provide a resilient closed lower end 10' from which extend laterally spaced leg members 11' and 12'. Said leg members terminate in inwardly extending and lapped arms 13' and 14' from which depend opposed jaw portions 15' and 17'. Formed in connection with the lower ends of the respective jaw portions of 15' and 17' are out-turned arcuate stop members 19 and 20. Said stop members are laterally bowed or bent so that their free ends 21 and 22 lie substantially in the plane of the leg members 11' and 12', whereby, upon inward movement of the latter, in opposition to the biased tension thereof, separating movement of the jaw portions 15' and 17' is limited by impingement of said free ends 21 and 22 of the stop members upon the inner sides of the respective leg members (see Fig. 6). By pressing the leg members 11' and 12' one toward the other, in directions of the arrows in Fig. 6, the jaw portions 15' and 17' are separated for reception or release of a cigarette, as the case may be.

From the above it will now be understood that this invention provides a very practical means for so hold-

ing a cigarette during smoking thereof that necessity for handling the same by the fingers is avoided, and consequently risk of nicotine staining of the fingers is eliminated. Furthermore, the cigarette smoke is not contaminated by necessity for flow through passages in which tarry and oily residues of smoke fumes have previously collected, as is the case when tubular cigarette holders are used. The holding tongs of this invention will automatically snuff out a cigarette when it burns down to the gripping jaw portions. The tongs can be laid on marginal portions of a table, desk or like supporting surface, so that the cigarette held therein can not contact and char said surface. The above and many other advantages are incident to the use of the cigarette holding tongs of this invention.

Having now described my invention, I claim:

A cigarette holding tongs comprising a one-piece body formation produced from stiff springy wire doubled upon itself to provide a pair of leg members tensionally biased for relative outward movement, said leg members terminating in inwardly projecting and lapped arms, opposed arcuate cigarette gripping jaw portions dependent from said arms to lie intermediate said leg

members and to be yieldably biased by the latter for movement one toward the other, and said jaw portions terminating in crossed and lapped outwardly bowed tail pieces, whereby parts of the jaw portions lie in the plane of and in opposition to the leg members so as to impinge upon the latter with limiting effect upon the separating movement of said jaw portions, while mutual impingement of intersecting points of said jaw portions and said tail pieces operates to limit tensional closing movements of said jaw portions, whereby to grip an interposed cigarette without undue squeezing restriction.
